UNITED STATES PATENT OFFICE.

JOHN WETHERED BELL, OF CONOWINGO, MARYLAND.

WATCH-HANDS.

SPECIFICATION forming part of Letters Patent No. 267,824, dated November 21, 1882.

Application filed May 25, 1882. (No model.)

To all whom it may concern:

Be it known that I, JOHN WETHERED BELL, of Conowingo, in the county of Cecil and State of Maryland, have invented a new and useful Improvement in Watch-Hands; and I do hereby declare that the following is a full, clear, and exact description of the same, reference being had to the accompanying drawings, forming part of this specification.

10 My invention relates to an improvement in watch-hands, designed to enable the wearer to see at a glance the different times of the place he is leaving and the place which constitutes his destination, or to enable him with one watch 15 to keep both standard and local time. The value to the traveling public of such a device is apparent in the facility which it affords for making connections between trains run by different times, as well as in keeping appointments between different cities. Some efforts to provide such a device have been made heretofore, as shown, for instance, in the expired patent to Hall, No. 47,065, granted March 28, 1865, and others of a later date, in which patent two hands 20 were coupled so as to move together in the normal action of the watch, but still have an independent adjustment with respect to each other to point to different figures on the dial indicating the different times of different places.

25 My invention, while looking to substantially the same result, provides a more simple and practical construction for uniting the two hands; and it consists in turning a groove upon the hub of one hand, and providing the other hand 30 with a split spring-ring which is sprung into said groove, and which by its elasticity preserves a constant and uniform frictional contact with the other hand, that always maintains its proper relation during the normal 35 movement of the hands, but still permits an adjustment between them to adapt them to point to different times when it becomes necessary to adjust them to the longitude of different places.

40 In the drawings, Figure 1 is a view of the supplemental hour-hand. Fig. 2 is a sectional side view of the two hour-hands coupled together; Fig. 3, a sectional side view of the two minute-hands coupled together. Fig. 4 is a top view of the two hour-hands coupled together; Fig. 5, a top view of the two minute-hands coupled. Figs. 6 and 7 are sectional side views of the coupled hour and minute hands, showing a modified or angular form of groove for

coupling said hands. Fig. 8 is a face view of 55 a watch provided with my improvement.

In carrying out my invention I take the ordinary hour-hand, A, as provided with a hub, b, fitting the hour-hand sleeve, and cut in it a groove, c, and into the groove I spring, by 60 reason of the split or opening a', the ring portion of the supplemental hand A'. The ordinary minute-hand, B, having perforated boss d, I groove in a similar way, and spring into this groove the split ring of the supplemental minute-hand B' by virtue of the opening b'. It will thus be seen that the supplemental minute-hand B' and the supplemental hour-hand A' will be held to the ordinary hands, A and B, by a frictional contact, and when placed upon 70 the arbors of the watch the two hands of such pair will move together and maintain the same relative angular position, one hand of each pair indicating one time and the other another. If the time is to be changed, the supplemental 75 hands are set to a new angular adjustment. In fastening on the supplemental hand I may make the groove c either a round groove, as in Figs. 2 and 3, or an angular groove, as in Figs. 6 and 7, the latter being preferred for the reason that the frictional contact is more perfect. 80

Though having greatest value for watches or portable time-pieces, my invention is also applicable to clocks and all kinds of time-pieces.

If desired, the hands of the same division of 85 time may be turned into exact registration, so as to show but two hands on the face of the watch.

In defining my invention more clearly with respect to the prior state of the art, I would 90 state that I am aware that a split ring is not broadly new in its application to other uses, and I do not claim it separately.

Having thus described my invention, what I claim as new is—

The combination of a pair of coupled hands, one of which has a peripheral groove with inclined sides cut around its hub, and the other a split spring-ring sprung into the groove and around the hub for the purpose of preserving a constant frictional contact between the two and maintaining a definite angular relation between the hands for correctly indicating the differences in time, as set forth.

JOHN WETHERED BELL.
